UNITED STATES PATENT OFFICE.

WILLIAM E. GREENAWALT, OF DENVER, COLORADO.

ELECTROLYTIC APPARATUS.

1,186,898.

Specification of Letters Patent. Patented June 13, 1916.

Application filed August 28, 1913. Serial No. 787,139.

To all whom it may concern:

Be it known that I, WILLIAM E. GREENAWALT, a citizen of the United States, and resident of the city and county of Denver 5 and State of Colorado, have invented certain new and useful Improvements in Electrolytic Apparatus, of which the following is a specification.

This invention represents a modification 10 of my application, Serial No. 665,742, filed December 14, 1911, and has for its more immediate object the employment of vertical electrodes and exceedingly large current, so that large units may be employed and the 15 floor space correspondingly diminished. By this invention high cathode and anode efficiencies may be realized, the disintegration of the anodes reduced to a very small amount, and the deleterious reactions of the 20 ferric and ferrous salts reduced to a minimum.

Referring to the accompanying drawings, Figure 1 is a longitudinal section of the apparatus, Fig. 2 the corresponding plan, Fig. 25 3 a transverse section, Fig. 4 a detail section of the preferred construction of the electrolyte cell, and Fig. 5 the corresponding plan.

In the figures 1 represents a tank containing 30 the electrolyte, in which is suspended the electrode cell 2, by the flexible suspenders 9, from the beams 8, supported by the posts 7. The anode bell is arranged so as to oscillate when actuated by the mechanism 10, which 35 may be a driving rod attached to a crank or eccentric mounted on a shaft, and driven by a pulley 11.

The electrode bell, or cell, is preferably 40 constructed by bolting diaphragms 3 to the pieces composing the sides of the cell 4. The diaphragms 3, are composed of mullioned frames between which is sandwiched the dia- 45 phragm fabric. The cells may be arranged, if more than one compartment is desired, as 50 shown in the left of Fig. 2, so that each may act more or less independently, but the preferred arrangement is shown in the right half, in which all the individual compartments are bolted together to act as a whole, 55 so that the entire electrode cell may be oscillated by the mechanism 10. This is shown in detail in Figs. 4 and 5, in which 12 is the bolt, 4 the pieces composing the sides of the electrode cell, 3 the diaphragm, and 13 pieces along the sides between which the dia-

phragm and cell pieces are bolted, and which are preferably arranged to protect the bolt heads by having a portion countersunk. Into this countersunk hole or groove and covering the bolt heads is then inserted some 60 sealing material, such as acid proof cement, hard tar, or wood, thus preventing the corrosive electrolyte from destroying the bolts. The bolt heads may also be incased in lead, and in addition the lead may be protected by 65 an insulating paint or lacquer.

The anodes are represented by 5, and are shown as bolted together by the bar 15, which may also act as an electrical conductor. The anodes are suspended by the 70 rods 16, from the beams 17. They may also oscillate, but are preferred stationary. The cathodes are shown by 6, and are suspended by rods 18 from beams 19. These may also oscillate but are preferred stationary. The 75 electrode cell is preferably oscillated from fixed pivotal points, as shown, but any other method of oscillation will accomplish the same results, but not as effectively and at greater expense. The rate of oscillation will 80 usually vary with the current density, from 20 to 60 oscillations per minute gives good results.

In the cathode compartment, in the bottom piece of the electrode cell, are preferably 85 arranged openings 20, so that any non-adherent electrode material may be worked through the holes by the oscillating cell into the bottom of the electrolyte tank 21, and then removed from time to time through the 90 pipe 22 and valve 23. Similarly, the non-adherent electrode material may be removed from the anode compartment, in suspension in the electrolyte, by the oscillating electrode cell and the flexible duct 24. The ordinary 95 method of operation will be to introduce the electrolyte into the electrolyte tank and consequently into the cathode compartment of the electrode cell, from which the electrolyte may pass through the diaphragm into 100 the anode compartment, and pass out through the flexible duct 24, which connects the oscillating electrode cell with the stationary electrolyte tank, and permits of the withdrawal of the exhausted electrolyte 105 without coming in direct contact or mingling with the catholyte.

It will be understood that it is quite im- 110 material which is the anode and which is the cathode compartment in the electrode cell;

the choice will be purely a matter of convenience.

The electrode accumulation in the electrolyte tank may be removed from time to time, as convenient, and the electrode material removed from the electrolyzer in suspension with the electrolyte through the flexible duct 24 may be removed by filtration or by decantation, and if desired the clarified electrolyte may be returned to the electrolyzer.

The preferred arrangement of the apparatus is to have the different compartments bolted together so that the electrode cell will have both anode and cathode compartments, and oscillated together in the electrolyte tank. In this way both the anolyte and catholyte are effectively agitated, and, as the catholyte passes through the diaphragm into the anode compartment and is then exhausted through the flexible tube 24 there is little chance for the ferric compounds getting back to the cathode and reducing the current efficiency, either through impoverishment of the electrolyte at the electrodes or by useless oxidation and reduction.

In some electrolytic processes, as for example in the electrolysis of copper solution with graphite or magnetite anodes, the diaphragm fabric, while always beneficial, may be omitted, in which case the mechanical action of the apparatus will be much the same, and great advantage is still derived from its use. With the diaphragm fabric omitted the frames, including the mullions or cross-pieces will act as effective agitators for the electrolyte and improve the electrolytic action both at the anode and cathode and overcome many other difficulties. The agitation is effective, due largely to the cross-pieces which should be at least as close together as the amplitude of oscillation.

I claim;

45 1. In electrolytic apparatus, an electrolyte tank, an anode and a cathode suspended vertically within the electrolyte tank, a diaphragm separating the anode from the cathode and suspended so as to be capable of being oscillated, and means for oscillating the diaphragm within the electrolyte tank.

50 2. In electrolytic apparatus, an electrolyte tank, an anode and a cathode suspended vertically within the electrolyte tank, a diaphragm separating the anode from the cathode and suspended so as to be capable of being oscillated, and means for oscillating the diaphragm from fixed pivotal points.

55 3. In electrolytic apparatus, an electrolyte tank, anodes and cathodes suspended vertically within the electrolyte tank, a diaphragm surrounding the electrodes of one sign thus forming electrode cells alternating with the electrodes of the opposite sign, means for suspending the diaphragm within

the electrolyte tank so as to be capable of being oscillated, and means for oscillating the diaphragm.

4. In electrolytic apparatus the combination of an electrolyte tank containing the electrolyte and vertical cathodes, a vertical anode suspended within the electrolyte tank and independently of the cathodes, a diaphragm suspended within the electrolyte tank independently of the electrodes and capable of being oscillated, and means for oscillating the diaphragm independently of the electrodes and the electrolyte tank.

5. In electrolytic apparatus the combination of an electrolyte tank containing the electrolyte and vertical cathodes, anodes suspended within the electrolyte tank, a diaphragm completely surrounding the anode thus forming an anode cell, means for oscillating the diaphragm, and means for withdrawing the anolyte without mingling with the catholyte.

6. In electrolytic apparatus, a vertical anode and a vertical cathode suspended within the electrolyte tank, a diaphragm separating the anode from the cathode, and means for moving the diaphragm through the electrolyte in the electrolyte tank.

7. In electrolytic apparatus the combination of an electrolyte tank, an anode and a cathode suspended within the electrolyte tank, a diaphragm separating the electrodes, means for oscillating the diaphragm through the electrolyte in the electrolyte tank, and means for withdrawing the electrolyte from the space inclosed by the diaphragm without mingling with the electrolyte in the electrolyte tank.

8. In electrolytic apparatus the combination of an electrolyte tank, an anode and a cathode suspended within the electrolyte tank, a diaphragm and diaphragm frame inclosing the electrodes thus forming anode and cathode compartments, said diaphragm frame having openings in the bottom communicating with the electrolyte tank for the removal of the non-adherent electrode material, means for oscillating the diaphragm within the electrolyte tank, and means for withdrawing the electrolyte from the space inclosed by the diaphragm without mingling with the electrolyte in the electrolyte tank.

9. In electrolytic apparatus the combination of an electrolyte tank, a stationary anode, a stationary cathode, a diaphragm and diaphragm frame separating the electrodes thus forming anode and cathode compartments suspended within the electrolyte tank, and means for oscillating the diaphragm and diaphragm frame.

10. In electrolytic apparatus the combination of an electrolyte tank, a stationary anode, a stationary cathode, a diaphragm and diaphragm frame separating the anode from the cathode said diaphragm frame

- having means for permitting the non-adherent electrode material to pass from the electrodes to the electrolyte tank, and means for oscillating the diaphragm and dia-
5 phragm frame.
11. In electrolytic apparatus having a plurality of anodes and cathodes, a plurality of frames having cross-pieces interposed between the electrodes and bolted together to
10 act as a whole, and means of oscillating said frames and cross-pieces from fixed pivotal points.
12. In electrolytic apparatus, frames having vertical cross-pieces; side pieces, on a
15 line with the electrodes, interposed between the frames; means of securing the frames to the side pieces, and means of oscillating the frames and cross pieces from fixed pivotal points.
- 20 13. In electrolytic apparatus frames having vertical cross-pieces interposed between the electrodes; side pieces alternating with
- the frames; means of securing the frames to the side pieces, and means of oscillating the frames and cross pieces from fixed pivotal 25 points.
14. In electrolytic apparatus frames having vertical cross-pieces interposed between the electrodes; peripheral side pieces alternating with the frames; bolts securing the 30 frames and side pieces together; means of protecting the bolt heads from the corrosive action of the electrolyte, and means of oscillating the agitator thus formed from fixed pivotal points.
15. In electrolytic apparatus a frame work completely surrounding the electrode and having vertical cross-pieces, means of oscillating said frame work and cross-pieces.
